UNITED STATES PATENT OFFICE

MICHAEL LIPTAK, OF ST. PAUL, MINNESOTA

FIRE WALL

Application filed November 1, 1928. Serial No. 316,513.

This invention relates to improvements in fire walls and has, among its objects, to provide a wall comprising two sections one of which is herein called the permanent wall and the other of which is called the replaceable wall, the latter wall being connected with the former so that its elements may be replaced when burned out, and this replaceable wall being that one which is directly exposed to the heat.

Specific objects are to provide means for tying the wall sections together; to provide tie elements and means forming part of the permanent wall, and extending across the space between the walls in a manner to reinforce or support these tie elements; to provide a hollow fire wall having a replaceable portion, in which certain elements of the replaceable portion are arranged to provide dead air spaces, and in some instances to make such spaces continuous throughout the longitudinal extent of the wall; to provide an arrangement of the elements of the replaceable wall so that the dead air spaces above mentioned may communicate with the inner-wall space; to provide an air space between the walls, and to so construct the wall that it is as strong as a solid wall, this object being accomplished by providing what may be termed a cantilever arrangement whereby elements are provided which extend beneath the tie elements across the space between the walls, but which supporting elements do not extend into the replaceable wall; to provide a refractory mortar joint, that is such a joint as will permit the tie elements which extend into both walls to be easily loosened and removed from the permanent wall, thus obviating the necessity for chiseling out the brick for replacement; to provide superposed courses of headers each supported by an element which is anchored in the permanent wall and which extends across the space between the walls, and to further provide space elements between these headers so that the superposed wall inter-spaces between superposed courses of headers may intercommunicate vertically throughout the wall, and to also provide an arrangement in which no such intercommunication is had,

and to prevent this intercommunication by means of header elements, arranged only in the replaceable wall, or portion.

Features and advantages of the invention will be disclosed in the description of the drawings forming a part of this application, and in said drawings:

Figure 1 is a perspective view, with portions removed to more clearly illustrate the construction;

Figure 2 is a plan section substantially on line 2—2 of Figure 4;

Figure 3 is a plan section substantially on line 3—3 of Figure 4;

Figure 4 is a vertical section taken on lines 4—4 4—4 of Figures 2 and 3;

Figure 5 is a vertical section taken substantially on lines 5—5 5—5 of Figures 2 and 3;

Figure 6 is a view corresponding to Figure 5 but showing a modification in which header elements arranged in the replaceable wall extend into the wall inter-space; and

Figure 7 is a plan section on line 7—7 of Figure 6.

The permanent wall portion is, in this instance, built between and supported by longitudinally extending horizontally arranged channel irons 1, which form part of a structure which is disclosed in my Patent Number 1,665,556. Although the supporting means for these channel elements have not been shown, it will be understood that they are properly supported at opposite ends and that they are cross-connected. Of course, the use of these iron is not necessary to the present invention and they have only been used for purposes of illustration. Between these superposed irons are arranged bricks in alternate header and stretcher courses in a manner to provide superposed rows of horizontally aligned sockets. As far as the broad feature of the invention is concerned, it is immaterial how the wall is formed, except that it provides these sockets, or their equivalent, the bottom-forming members of which extend across the space between the walls but not into the replaceable wall. As hereinafter explained, these members form supports for the tie members which have ends arranged

in the socket, and which ties have the outer ends extending beyond the bottom-forming elements of the sockets, to support the replaceable wall at a point beyond the inner ends of said bottom-forming elements.

The socket bottom-forming elements are indicated at 5, and as shown have the form of substantially thick header elements some of which are laid upon the channels 1 and project beyond the inner face of the permanent wall. It will be understood that each of these elements could be a metal plate, the main feature being that each extends beyond the wall for the purpose above stated. The reinforcing elements 5 have arranged between them, see Figure 3, header elements 7 of less length than the elements 5, so that vertical spaces 8 are formed. Upon the top of the elements 5 are arranged bricks 9, (see Figure 2) which abut bricks 10, which, in turn, overlie the bricks 7. The length of the element 10 is substantially the same as the length of the element 7 so that the vertical air circulating spaces 8 are maintained. By inspection of Figure 2, it will be seen that the bricks 9 and 10 together with header 5, and cap bricks or slabs 11 form the sockets above referred to. The cap bricks engage the upper surfaces of bricks 9 and 10. The bricks filling the spaces above and below the sockets include headers 12 and stretchers 13 and 14. The bricks 14 are facers for the channel irons 1.

In each socket, in this instance, are placed two elongated header elements, each pair of which is, therefore, supported by an element 5. These long header or tie elements are indicated at 15 and project beyond the bottom-forming elements 5 as best shown in Figure 1. The length of this projection beyond the ends of the elements 15, is, in this instance, substantially equal to the depth or thickness of the replaceable wall which is composed of bricks arranged between and supported only by the long headers 15. The brick of the replaceable wall can be arranged in other ways, but herein include stretcher courses composed of outer and inner rows of bricks, the members of which are respectively indicated at 18—19. This replaceable wall, in this instance, includes alternate header and stretcher courses, the stretcher courses including the members 18 and 19 and the header courses including the bricks 20. Between adjacent pairs of long tie header elements 15, and lying within the area of the replaceable wall portion are header elements 21, see Figures 1 and 5, which are of a length substantially equal to the thickness of the replaceable wall. These elements as well as the elements 7 and 10, see Figures 1 and 2, cooperate to provide the spaces 8 which permit communication between the horizontal inter-wall spaces formed between the superposed courses of long head-

ers. This arrangement is a feature of the invention, as is also the arrangement shown in Figures 6 and 7 in which the elements 22 corresponding to the elements 21 are extended across the space between the wall to close the spaces 8 and therefore interrupt communication between the opposing horizontal inter-wall space, but to further strengthen the wall, and yet provide dead air space proper for the purpose in hand.

Another important feature of the invention is the arrangement of the elements 18 and 19 to form longitudinally extended dead air spaces 25 in the replaceable wall. Another feature of the invention is the arrangement of the bricks 18, see Figure 3, in which the bricks of the stretcher courses are spaced apart as at 26 to provide inter-communication between the longitudinal spaces 25 and the wall inter-space.

It will be understood that although the blocks 9 are used, they may be dispensed with and the header elements 15 be extended from the outer face of the permanent wall to the outer face of the replaceable wall and therefore completely through both walls and across the space between them.

There is no intention to be limited to the particular shape or material of the reinforcing elements 5 or the dimensions thereof, inasmuch as the broad idea is to support the headers 15 in maximum degree across the wall inter-space without having the elements 5 enter or form a part of the replaceable wall.

Another feature of the invention is the arrangement of the element (or elements) 15 in the sockets so that each can be loosened after embedment in the mortar. Of course, in case the elements 9 are dispensed with and the headers 15 are extended flush with the outer surface of the permanent wall, special provision for removing the headers from the sockets of the perpendicular wall is not necessary inasmuch as the elements 15 can be hammered in a lengthwise direction for removal, the blows being applied either at the inner or outer side of the headers. However, under some conditions it is best to use the elements 9 and in this instance special provision is made for loosening the headers. To this end the depth of the socket from the top of the supporting elements 5 to the bottom of the slabs 11 is made greater than the depth or thickness of the elements 15 so that when the elements 15 are placed, a space is left above them which is filled with mortar as at 28. As shown in the drawing, the elements 9 are of the same height as the thickness of the headers 15 so that the mortar 28 also overlies them, that is, is continuous over both the upper surfaces of the elements 15 and the elements 10. Of course, as before stated, when the elements 15 pass completely through both walls the construction immediately above described is unnecessary. However, as shown

in the drawings, it will be seen that the socket is of a size to permit loosening of the headers after embedment in the mortar.

Although it is understood that the various features of the invention are all claimed broadly, it is also to be understood that all details of construction are also claimed.

I claim as my invention:

1. A permanent wall and a replaceable wall spaced therefrom, headers extending into both walls and across the space between them, and elements as part of the permanent wall arranged below the first mentioned headers as supports and extending into the space between the walls, but not into the replaceable wall.

2. A permanent wall having rows of horizontally aligned sockets, each socket having a header forming its bottom wall and extending beyond the permanent wall, a header resting upon each bottom-forming header and extending therebeyond, and a replaceable wall comprising bricks arranged between and supported only by the last mentioned headers.

3. A permanent wall having rows of horizontally aligned sockets, each socket having a header forming its bottom wall and extending beyond the wall, a header resting upon each bottom-forming header and extending therebeyond, and a replaceable wall comprising bricks arranged between and supported only by said last mentioned headers at a point beyond but immediately adjacent said bottom-forming headers, and including

4. alternate header and stretcher courses, the elements of the stretcher courses being spaced in a direction transversely of the wall to provide dead air spaces, and the innermost elements of the said stretcher courses, being arranged to establish communication between the dead air spaces and the space between the permanent and replaceable walls.

4. A permanent wall having rows of horizontally aligned sockets, each socket having a header forming its bottom wall and extending beyond the wall, a header resting upon each bottom-forming header and extending therebeyond and a replaceable wall comprising bricks arranged between and supported

5. only by said last mentioned headers at a point beyond but immediately adjacent said bottom-forming headers, and including alternate header and stretcher courses, the elements of the stretcher courses being spaced in a direction transversely of the wall to provide dead air spaces.

5. A permanent wall having rows of horizontally aligned sockets, each socket having a header forming its bottom wall and extending beyond the permanent wall, a header resting upon each bottom-forming header and extending therebeyond, and a replaceable wall comprising bricks arranged between and supported only by the last mentioned head-

ers, at a point beyond but adjacent said bottom-forming headers.

6. A permanent wall, a replaceable wall spaced from said permanent wall, headers extending across the space between and into both walls and elements having ends removably arranged within the permanent wall and extending across the space between the walls but not entering the replaceable wall and forming supports for headers.

7. A permanent wall, and a replaceable wall spaced therefrom, headers extending into both walls and across the space between them, and elements as part of the permanent wall arranged below the first mentioned headers and reinforcing them, and extending entirely across the space between the walls but not into the replaceable wall.

8. A permanent wall and a replaceable wall spaced therefrom, headers extending into both walls and across the space between them, and elements as part of the permanent wall and detachably secured therein and arranged below the first mentioned headers and reinforcing them and extending entirely across the space between the walls but not into the replaceable wall.

9. A permanent wall and a replaceable wall spaced therefrom, headers extending into both walls and across the space between them, and elements as part of the permanent wall arranged below the first mentioned headers and reinforcing them and extending entirely across the space between the walls but not into the replaceable wall, the headers being arranged in spaced superposed courses, and those portions of the permanent wall arranged between superposed courses of headers including alternate header and stretcher courses, the elements of the stretcher courses being spaced in a direction transversely of the wall to provide dead air spaces, and the innermost elements of said stretcher courses being arranged to establish communication between said dead air spaces and the inter-

10. wall spaces.

10. A permanent wall and a replaceable wall spaced therefrom, headers extending into both walls and across the space between them, and elements as part of the permanent wall arranged below the first mentioned headers and reinforcing them and extending entirely across the space between the walls but not into the replaceable wall, the headers being arranged in spaced superposed courses, and additional header elements arranged in the replaceable wall between those headers which extend into both walls.

11. A permanent wall having superposed spaced rows of headers extending therebeyond and a replaceable wall comprising bricks arranged between and supported by the headers, and including alternate header and stretcher courses, which courses include rows, said rows being spaced transversely of

120
125
130

the wall to provide continuous dead air spaces lengthwise thereof.

12. A permanent wall having superposed spaced rows of headers extending therebeyond, and a replaceable wall comprising bricks arranged between and supported by the headers, and including alternate header and stretcher courses, which courses include rows, said rows being spaced transversely of the wall to provide continuous dead air spaces lengthwise thereof, and said walls being spaced apart, and the members of that row of stretchers adjacent the space between the walls having their ends spaced apart to form intercommunication between the space between the walls and the air spaces between the rows of the bricks of the replaceable wall.

13. A permanent wall having vertically spaced rows of horizontally aligned sockets therein, each socket having a bottom-forming element which extends beyond the wall, a header resting upon each bottom-forming element and arranged in the socket and extending beyond said bottom-forming element, and a replaceable wall comprising bricks arranged and supported only on the headers at a point beyond the bottom-forming elements, the height of the sockets above the bottom-forming elements being less than that of the headers to permit loosening of the headers after embedment in mortar.

14. A permanent wall having vertically spaced rows of horizontally aligned sockets therein, each socket having a header forming its lower wall and extending beyond the wall, a header resting upon each bottom-forming header having an end arranged in the socket and extending beyond the header, and a replaceable wall comprising bricks arranged between and supported only by the last mentioned headers at a point beyond and immediately adjacent the first mentioned headers, the socket being of a size to permit loosening of the headers, after embedment in mortar.

15. A permanent wall, a replaceable wall spaced therefrom, horizontally arranged and vertically spaced rows of supporting elements embedded in the permanent wall and extending across the space between the walls, but not extending into the replaceable wall, and headers resting upon said supporting elements and extending into both walls to tie them, the arrangement being such that those portions of the headers which extend across the space between the walls are supported for the full distance across that space.

16. A permanent wall having headers extending therebeyond, a replaceable wall comprising bricks arranged between and supported by the headers, and including header and stretcher courses, the stretcher courses including rows spaced from each other in direction transversely of the wall to provide longitudinal dead air spaces.

17. A permanent wall having headers extending therebeyond, a replaceable wall comprising bricks arranged between and supported by the headers, and including stretcher courses, including rows spaced from each other in direction transversely of the wall to provide dead air spaces.

18. A permanent wall having headers extending therebeyond, a replaceable wall comprising bricks arranged between and supported by the headers, and including stretcher courses, including rows spaced from the other in direction transversely of the wall to provide dead air spaces, said permanent and replaceable walls being spaced apart, and the innermost row of elements of said stretcher courses having their ends spaced apart to establish communication between the dead air spaces of the permanent wall and the inter-wall spaces of the permanent and replaceable walls.

19. A permanent wall and a replaceable wall spaced therefrom, headers extending into both walls and across the space between them, and elements as part of the permanent wall arranged below the first mentioned headers and reinforcing and extending entirely across the space between the walls but not into the replaceable wall, the headers being arranged in spaced superposed courses, and those portions of the permanent wall arranged between superposed courses of headers including alternate header and stretcher courses, the elements of the stretcher courses being spaced in a direction transversely of the wall to provide dead air spaces, and the innermost elements of said stretcher courses being arranged to establish communication between said dead air spaces and the inter-wall spaces, and additional header elements arranged in the replaceable wall between those headers which extend into both walls and of a length substantially equal to the thickness of the replaceable wall.

In witness whereof, I have hereunto set my hand this 26th day of October, 1928.

MICHAEL LIPTAK.
